DESIGN FOR A SUPPORT FOR A BAR OF SOAP OR SIMILAR ARTICLE

Raymond R. Ward, Brecksville, Ohio

Application February 17, 1948, Serial No. 144,547

Term of patent 7 years

(Cl. D4—3)

To all whom it may concern:

Be it known that I, Raymond R. Ward, a citizen of the United States and a resident of Brecksville, in the county of Cuyahoga and State of Ohio, have invented a new, original, and ornamental Design for a Support for a Bar of Soap or Similar Article, of which the following is a specification, reference being had to the accompanying drawings, forming a part thereof.

In said drawings,

Fig. 1 is a top plan view of a support for a bar of soap or similar article, showing my new design;

Fig. 2 is a side-elevational view of such support; and

Fig. 3 is a vertical sectional view of such support, on the line 3—3, Fig. 1.

In all views, the dominant feature of my design is shown in full lines.

I claim:

The ornamental design for a support for a bar of soap or similar article, substantially as shown and described.

RAYMOND R. WARD.
